Primary Examiner — Gino Colan*Assistant Examiner* — Gregory G McLemore(74) *Attorney, Agent, or Firm* — Daryl R. Wright; Greg Carr(57) **CLAIM**

We claim the ornamental design for a model vehicle wing, as shown and described.

DESCRIPTION

FIG. 1 is an upper, left, front perspective view of a model vehicle wing showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is an upper plan view thereof;

FIG. 7 is a lower plan view thereof;

FIG. 8 is an upper, right, rear perspective view thereof; and,

FIG. 9 is a lower, right, rear perspective view of the model vehicle wing.

In the drawings, the broken lines illustrate portions of the model vehicle wing that form no part of the claimed design.
